UNITED STATES PATENT OFFICE

JAMES A. LONG, OF READING, PENNSYLVANIA, ASSIGNOR TO PENN ENGINEERING COMPANY, OF READING, PENNSYLVANIA, A PARTNERSHIP COMPOSED OF JAMES A. LONG, CLEVE E. LONG, J. EDWIN TOTHERO AND HARRY A. KISSINGER.

VISE STAND

Application filed November 27, 1929. Serial No. 410,130.

The invention relates to improvements in stands such as those commonly used by plumbers, steam-fitters and other mechanics for supporting vises, pipe benders or other equipment.

It is one object of the invention to provide a new and improved construction for connecting the legs with the top plate and allowing said legs to swing inwardly from operative inclined positions to substantially vertical positions, the construction being such that there is no danger of breaking any parts of the pivotal connections during ordinary use, or during shipment or rough handling.

15 A further object is to provide novel means for limiting the inward swinging of the legs.

A still further aim is to make unique provision for holding the legs against accidental inward swinging.

20 With the foregoing in view, the invention resides in the novel subject matter herein-after described and claimed, description being accomplished by reference to the accompanying drawings.

25 Fig. 1 is a perspective view with the lower portions of the legs broken away.

Fig. 2 is a vertical sectional view on line 2—2 of Fig. 1.

30 Fig. 3 is a horizontal sectional view on line 3—3 of Fig. 2.

In the drawings above briefly described, the numeral 5 denotes a suitably shaped top plate provided with various openings 6 instrumental in attaching equipment thereto, 35 with an opening 7 to receive a pipe to be bent, and with a pipe-bending rest 8. The lower side of the plate is suitably ribbed as at 9 for reinforcing purposes, wherever advisable.

40 Integral with and projecting downwardly from the plate 5, are a number of socket members 10 which receive the upper ends of the legs 11, said legs being pivoted to said socket members at 12, for inward and outward swinging. The gist of the invention resides in the construction of the socket members 10 and in their relation with the legs 11 and as such construction and relation are identical in connection with all of the sockets

and legs, only one socket and leg will be specifically described.

The socket 10 embodies two spaced vertical side walls 13, an outer end wall 14 integral with said side walls, and an inner end wall 15 also integral with said side walls. The side walls 13 are preferably stepped so that greater length is imparted to the outer portions of the sockets 10 than to the inner portions, but this exact configuration is not essential.

The pivot 12 is spaced inwardly from both of the walls 14—15, is spaced downwardly from the upper extremity 16 of the leg 11 and is spaced upwardly to a slight extent from the lower extremity of the outer end wall 14, and said leg extremity 16 is permanently spaced downwardly from the top plate 5. The relation of parts is such that when the leg 11 is swung outwardly to its operative position, 70 said extremity 16 thereof abuts the end wall 15 while a portion of the leg below the pivot 12 abuts the lower extremity of the outer end wall 14. Hence, the outward swinging of the leg is effectively limited and said leg can exert no lever-like strain upon the pivot 12 tending to shear the latter. When the leg is swung inwardly to its retracted substantially vertical position, seen in dotted lines in Fig. 2, its extremity 16 abuts the outer end wall 14 and hence limits such inward swinging of the leg.

The opposed side walls 13 of the socket 10 are provided with inwardly distorted portions 17 providing humps past which the leg 85 11 snaps when said leg is swung outwardly to operative position, said humps then serving to prevent accidental inward swinging of the leg, not only providing a stand which may be more readily positioned for use, but 90 providing a more rigid construction during use.

The construction may be such that either the walls 13 or the pipe 11, or both may spring as the legs snap past the humps 17, incident to 95 outward and inward swinging of said legs.

By providing the novel construction shown and described or a substantial equivalent thereof, a stand is provided which will effectively attain the objects of the invention.

The details disclosed have proven highly ad-
vaontageous from all standpoints and are
preferably followed. However, within the
scope of the invention as claimed, variations
5 may be made.

I claim:—

1. A stand comprising a top plate having
pairs of downwardly projecting parallel
walls, legs whose upper ends are pivoted be-
tween said walls in position to at all times
10 clear said top plate, means for limiting the
outward swinging of said legs to their opera-
tive positions, and humps integral with said
side walls and projecting inwardly there-
15 from in opposed relation with each other,
said humps being positioned to abut opposite
side portions of said legs and hold the latter
in their operative positions, portions of said
stand having sufficient inherent resiliency to
20 allow said legs to snap past said humps when
swinging said legs to and from operative
positions.

2. A tripod comprising a top plate having
downwardly projecting socket members, each
25 of said socket members having parallel side
walls disposed substantially radially of said
top plate, outer end walls integral with the
outer ends of said side walls, and inner end
walls integral with the outer ends of said side
30 walls, downwardly diverging legs whose upper
ends are received in said socket members, and
pivots below the upper extremities of said
legs passing through said legs and said side
walls and mounting the former to swing radi-
35 ally of said top plate, said pivots being dis-
posed to cause said legs to abut both said
inner and outer end walls when said legs are
in downwardly diverging relation and to
cause said leg extremities to strike said outer
40 end walls when the legs are inwardly swung
to substantially vertical positions.

3. A tripod comprising a metal top plate
having downwardly projecting socket mem-
bers, each of said socket members having
45 parallel side walls integral with and dis-
posed substantially radially of said top
plate, and inner and outer end walls in-
tegral with said top plate and said side
walls, metal legs whose upper ends extend
50 into said socket members, pivots pass-
ing through said legs and side walls and
mounting said legs in position to at all times
clear said top plate, said pivots being posi-
tioned to cause said legs to strike said inner
55 end walls above the pivots and said outer end
walls below the pivots when said legs are
swung outwardly to operative position, and
to cause said legs to strike said outer walls
above the pivots when said legs are swung in-
60 wardly to substantially vertical positions,
and hump integral with said side walls and
projecting inwardly therefrom in opposed re-
lation with each other, said humps being posi-
tioned to abut opposite side portions of said
65 legs and hold the latter in their operative po-

sitions, portions of said tripod having suf-
ficient inherent resiliency to allow said legs
to snap past said humps when swinging said
legs to and from operative positions.

In testimony whereof I have hereunto af- 70
fixed my signature.

JAMES A. LONG.
